PUSH BAR ASSEMBLY

Deane N. Jewett, Detroit, Mich., assignor to
 Detroit Hardware Manufacturing Company,
 Detroit, Mich., a corporation of Michigan

Application March 21, 1949, Serial No. 82,508

7 Claims. (Cl. 16—1)

1

This invention relates to building hardware, and in particular, to push-pull bars for doors.

One object of this invention is to provide a push-pull bar construction for attachment to the opposite sides of the door in such a manner that the attachment devices are concealed from view in an opaque door and show only two screws at the meeting ends of the bars in a transparent door.

Another object is to provide a blind attachment construction for push-pull bars for doors of either opaque or transparent construction, wherein the usual screw plates are eliminated and the only visible evidence of attachment in a door with an opaque door frame is the countersunk head of a single screw at each end of one of the push bars, even this screw head being visible only by looking up at the bar from beneath it.

Another object is to provide a blind attachment construction for push-pull bars for doors of either opaque or transparent construction wherein one of the bars is secured to the door frame by a pair of concealed screws at either end, and the other bar has its ends secured to the opposite side of the door frame by being attached to blocks held by the same pair of screws which hold the opposite push bar against the opposite side of the door.

Another object is to provide a blind attachment construction for push-pull bars for doors, as set forth in the object immediately preceding, wherein the second push bar is attached at its ends to the attachment blocks by pairs of studs having their heads seated in sockets in the blocks and secured therein by a single screw passing upward from beneath the block through the heads of both studs, thereby resulting in a completely concealed connection for opaque door frames when the push bars are viewed from any direction except upward from below one of the push bars.

In the drawings:

Figure 1 is a horizontal section through a door with an opaque door frame taken along the line 1—1 in Figure 4 and showing the push-pull bar construction of the present invention in top plan view, partly in horizontal section at the ends of the bars;

Figure 2 is a vertical longitudinal section along the line 2—2 in Figure 1;

Figure 3 is a vertical cross-section along the line 3—3 in Figure 1; and

Figure 4 is a reduced perspective view of a door equipped with the push-pull bar construction of Figures 1 to 3 inclusive.

2

Doors of commercial and residential buildings are frequently equipped with so-called "push-pull bars" for assisting persons to open and close the door by applying pressure to the bars in the appropriate direction. Such bars are frequently used on swinging doors so that the door may be opened from either direction by pushing or pulling the push bar on that side of the door. In the past, it has often been the practice to secure the ends of such push bars to the door by means of screw plates mounted on the opposite sides of the door. Such screw plates, however, are not only very visible but also are unsatisfactory for use with glass doors or doors with tubular metal frames which have very narrow stiles or backing plates. With transparent doors, moreover, such as are frequently found in modern stores, apartment buildings or the like, these prior attachment arrangements are ugly in appearance in contrast to the beauty and modernity of appearance of a completely transparent door having no door frame.

The push-pull bar construction of the present invention eliminates the disadvantages of these prior doors by securing each end of one of the push bars to the door or door frame by a pair of connecting screws threaded into the end from the opposite side of the door through a block having sockets which receive the heads of locating studs threaded into the adjacent end of the other push bar. The heads of the locating studs, in turn, are held in these sockets by a single anchoring screw passing upward through the head of the lower stud and threaded into the head of the upper stud. In this manner, only the head of a single screw is visible at each end of one only of the push bars, and even this screw head is countersunk into the bottom of the block and can be seen only by stooping so as to look up at the push bar from below.

Moreover, in the present invention, there is no need for the attachment plates or backing plates hitherto required, and the stiles of the door frame can be as narrow as desired, or may be omitted altogether, as in transparent frameless doors. In addition to the single anchoring screw at each end beneath one of the push bars, the only visible evidence of attachment, even in a transparent door, is the pair of screws passing through the door into each end of the other push bar. Thus, the number of parts in the present invention is not only reduced to a minimum but these parts are for the most part concealed from view. The finished push-pull bar construction, moreover, is of clean, modern-appearing design with no pro-

jecting parts or separate attachment members to mar the beauty of its appearance.

Referring to the drawings in detail, Figures 1 and 4 show a conventional door, generally designated 10, equipped with a push bar assembly, generally designated 11 which in turn includes push bars 12 and 13 and attachment blocks 14. The door 10 may be of any conventional construction, that shown having wood stiles or upright frame members 15 interconnected by horizontal members 16 and 17 at top and bottom respectively, these enclosing a glass central panel 18. This construction, however, may optionally be partly or wholly metallic, or the door may consist throughout of a single panel of transparent material such as glass, without any stiles whatever. The details of the door form no part of the present invention.

The push bars 12 and 13 have elongated central portions 19 and 20 in their opposite ends 21 and 22 bent into parallelism. The ends 21 are longer than the ends 22 (Figure 1) by the lengths of the blocks 14 so that the appearances of the push bar assemblies on opposite sides of the door will be substantially the same. The ends 21 of the push bar 19 are bored and threaded as at 23 to receive the threaded ends of attachment screws 24 passing through bores 25 in the stiles 15. A pair of screws 24, one above the other, is preferably used at each end of the push bar 19, and the shanks of these screws pass through bores 26 in each block 14. The bores 26 open into counterbores or sockets 27 which receive the heads of the screws 24.

The opposite ends 22 of the push bar 20 are bored and threaded as at 28 to receive the threaded portions of locating studs 29, the heads 30 of which are received in the sockets or counterbores 27 (Figure 2). The heads 30 are provided with bores 31 aligned with a bore 32 passing upward through the block 14 from a counterbore 33. The counterbore 33 receives the head of an anchoring screw 34, the shank of which passes through the lower bore 31 and is threaded into the upper bore 31 so as to secure the assembly together.

In attaching the push bar assembly 11 to the door 10, the latter is provided with vertically-spaced pairs of holes 25 at the desired level above the floor, and spaced to correspond with the threaded bores 23. The connecting screws 24 are then inserted in the sockets 27 with their shanks passing through the bores 26 and through the holes 25 in the door stiles 15, after which they are threaded into the threaded holes 23. When the attachment blocks 14 have thus been secured firmly to one side of the stile 15 and the push bar 12 to the other side, the studs 29 are threaded into their threaded sockets or holes 28 and turned until their transverse bores 31 are in alignment. They are then inserted in the sockets or counterbores 27 by pushing the ends 22 of the push bar 20 firmly against the blocks 14. While the parts are held in this position, the anchoring screws 34 are inserted from below into the counterbores 33, passed through the lower stud bore 31 and the attachment block bore 32 and threaded into the upper stud bore 31. When the anchoring screws 34 are tightened, their heads enter the counterbores 33 and accordingly become concealed therein.

In this manner, the push bars 19 and 20 are connected to the door 10 with a virtually invisible connection. If, however, it is desired to detach the push bars, this may be done by reversing the procedure just described. In disassembling the

push bar assembly 11, therefore, the anchoring screws 34 are first removed, thereby permitting the push bar 20 and its studs 29 to be withdrawn from the sockets 27 in the attachment blocks 14. This exposes the heads of the connecting screws 24 so that they may be removed by the use of a screw driver inserted in the sockets 27. The removal of the connecting screws 24 from the threaded bores 23 and the stile bores 25 releases the push bar 19 on one side of the door and permits the attachment blocks 14 to be detached from the other side of the door.

The concealed push bar construction of the present invention may also be used with certain types of swinging doors when the inner end of the push bar is bent toward the door and closely into parallelism with the door so as to avoid collision with the door frame when the door is swung to and fro. The outer ends of such push bars may employ the construction of the present invention as shown in the drawings and as described above.

What I claim is:

1. A concealedly-attached push bar assembly for a door, comprising a first push bar member having at least one of its ends adapted for abutting one side of the door, an attachment member adapted for abutting the opposite side of the door, a fastener adapted for extending through the door and interconnecting said members, a second push bar member having at least one of its ends engaging said attachment member, one of said two last-mentioned members having a portion penetrating the other thereof, and an anchoring element extending partially through the penetrated member into locking engagement with said penetrating portion with its axis disposed transversely thereto and securing said second push bar member to said attachment member.

2. A concealedly-attached push bar assembly for a door, comprising a first push bar member having at least one of its ends adapted for abutting one side of the door, an attachment member adapted for abutting the opposite side of the door, a fastener adapted for extending through the door and interconnecting said members, a second push bar member having at least one of its ends engaging said attachment member, and an anchoring element securing said second push bar member to said attachment member, one of said members on said opposite side of said door having a recess therein and the other member having a projection extending into said recess said anchoring element extending partially through the recessed member into locking engagement with said projection and with its axis disposed transversely to said projection.

3. A concealedly-attached push bar assembly for a door, comprising a first push bar member having at least one of its ends adapted for abutting one side of the door, an attachment member adapted for abutting the opposite side of the door, a fastener adapted for extending through the door and interconnecting said members, a second push bar member having at least one of its ends engaging said attachment member, and an anchoring element securing said second push bar member to said attachment member, one of said members on said opposite side of said door having a recess therein and the other member having a projection extending into said recess, said one member having a bore disposed transversely to said recess and said anchoring element being secured in said transverse bore and extending into locking engagement with said projection.

4. A concealedly-attached push bar assembly

for a door, comprising a first push bar member having at least one of its ends adapted for abutting one side of the door, an attachment member adapted for abutting the opposite side of the door, a fastener adapted for extending through the door and interconnecting said members, a second push bar member having at least one of its ends engaging said attachment member, and an anchoring element securing said second push bar member to said attachment member, one of said members on said opposite side of said door having a recess therein and the other member having a projection extending into said recess, said one member and said projection having aligned bores disposed transversely to said recess and said anchoring element being secured in said transverse bores and extending into locking engagement with said projection.

5. A concealedly-attached push bar assembly for a door, comprising a first push bar member having at least one of its ends adapted for abutting one side of the door, an attachment member adapted for abutting the opposite side of the door, a fastener adapted for extending through the door and interconnecting said members, a second push bar member having at least one of its ends engaging said attachment member, and an anchoring element securing said second push bar member to said attachment member, said attachment member having a recess therein and said second push bar member having a headed stud extending into said recess said anchoring element extending partially through the recessed member into locking engagement with said stud and with its axis disposed transversely to said stud.

6. A concealedly-attached push bar assembly for a door, comprising a first push bar member having at least one of its ends adapted for abutting one side of the door, an attachment member adapted for abutting the opposite side of the door, a fastener adapted for extending through the door and interconnecting said members, a second push bar member having at least one of

its ends engaging said attachment member, and an anchoring element securing said second push bar member to said attachment member, said attachment member having a recess therein and said second push bar member having a headed stud extending into said recess, the head of said stud having a transverse cavity therein, said anchoring element engaging said stud cavity and securing said stud in said recess.

- 10 7. A concealedly-attached push bar assembly for a door, comprising a first push bar member having at least one of its ends adapted for abutting one side of the door, an attachment member adapted for abutting the opposite side of the door, a fastener adapted for extending through the door and interconnecting said members, a second push bar member having at least one of its ends engaging said attachment member, and an anchoring element securing said second push bar member to said attachment member, said attachment member having a recess therein and said second push bar member having a headed stud extending into said recess, the head of said stud and said attachment member having aligned bores disposed transversely to said recess and said anchoring element extending partially through one of said transverse bores and being secured in the other transverse bore.
